DESIGN FOR A CAP

Milton A. Dannenberg, Chicago, Ill.

Application December 26, 1944, Serial No. 117,101

Term of patent 14 years

(Cl. D3—13)

To all whom it may concern:

Be it known that I, Milton A. Dannenberg, a citizen of the United States of America and a resident of the city of Chicago, county of Cook, and State of Illinois, have invented a new, original, and ornamental Design for a Cap, of which the following is a specification, reference being had to the accompanying drawing, forming a part thereof.

Fig. 1 is a front perspective view of a cap showing my new design,

Fig. 2 is a front elevational view thereof,
Fig. 3 is a side elevational view thereof on reduced scale, and

Fig. 4 is a rear elevational view thereof on reduced scale.

I claim:

The ornamental design for a cap, substantially as shown.

MILTON A. DANNENBERG.
